UNITED STATES PATENT OFFICE

ALBERT F. SONDERMAN, OF FERDINAND, INDIANA, AND NICHOLAS MEINHARDT, OF PRESTON, IOWA, ASSIGNEES TO F. H. SONDERMAN, OF YORKVILLE, INDIANA

DESIGN FOR A CHALICE

Application filed May 10, 1933. Serial No. 48,071. Term of patent 7 years.

To all whom it may concern:

Be it known that we, ALBERT F. SONDERMAN and NICHOLAS MEINHARDT, citizens of the United States and residents, respectively, of Ferdinand, in the county of Dubois and State of Indiana, and of Preston, in the county of Jackson and State of Iowa, have invented a new, original, and ornamental Design for Chalices, of which the following is a specification, reference being had to the accompanying drawing, forming part thereof.

The figure is a perspective view of a chalice, showing our new design.

We claim:

The ornamental design for a chalice, as shown.

ALBERT F. SONDERMAN.
NICHOLAS MEINHARDT.
